UNITED STATES PATENT OFFICE.

WILLIAM FILLMORE WOFFORD, OF STRATFORD, TEXAS.

DRAINAGE-BOTTLE.

1,256,857.

Specification of Letters Patent. Patented Feb. 19, 1918.

Application filed February 9, 1916. Serial No. 77,281.

To all whom it may concern:

Be it known that I, WILLIAM F. WOFFORD, a citizen of the United States, residing at Stratford, in the county of Sherman and State of Texas, have invented certain new and useful Improvements in Drainage-Bottles, of which the following is a specification.

My invention relates to new and useful improvements in drainage bottles.

10 The primary object of the invention is the provision of a drainage bottle which may be easily attached to or detached from the person and which is used for draining foreign substances from a wound in which a 15 drainage tube is used.

A further object of the invention is the provision of means for adjusting the bottle, so that it will fit persons of different sizes.

20 A still further object of the invention is the provision of an apron adapted to contact with the person and means for securing a bottle thereto.

25 With these and other objects in view, the invention consists in the novel details of construction and arrangement of parts which will be more clearly understood from the following description and drawings, in which,

30 The figure shown in the drawing is a perspective view of my invention.

In carrying out my invention I provide an apron 1 which is formed of rubber and said apron is provided on each side with an ear or extension 2 and on the top with an ear or 35 extension 3. Buckles 4 are secured to each of the ears or extensions 2, and a buckle 5 is connected to the extension 3, the purpose of which will be presently described. An opening 6 is formed in the apron 1 just below the 40 ear 3 and the purpose of which will be presently described.

An elastic belt 7 is provided for encircling the waist of the wearer and the free ends of the belt are adapted to be engaged by the 45 buckles 4. An elastic strap 8 is connected at one end to the belt 7 and the opposite end is adapted to be engaged by the buckle 5.

A ribbon or string 9 is adapted to be secured to the apron 1 and is adapted to en-

circle the neck of a rubber bottle 10. The 50 upper end of the bottle 10 is adapted to be secured in such position that it will be below the opening 6 formed in the apron 1. As is clearly shown in the drawing the ribbon or string 9 is adapted to be tied around 55 the neck. The bottle 10 preferably has the body portion formed of thin rubber thereby being very flexible and the top edge and neck or mouth may be made of heavier rubber for reinforcing. 60

Having described the detailed construction of my device, it is thought the advantages and mode of use will be clearly understood.

As previously stated in the object of my 65 invention I propose to provide a sanitary drainage bottle adapted for draining pus or other impurities from a wound, such as those caused by operations upon the various parts of the body. When it is desired to use my 70 bottle the apron 1 is placed in the most convenient place upon the body and the belt 7 will encircle the waist or other portion thereof. The strap 8 is adapted to pass over the shoulder to more securely hold the apron 75 in position. By passing the ends of the belt and strap through the buckles 4 and 5, the same may be adjusted to fit persons of various sizes. The bottle 10 is then secured in position by means of the ribbon or string 80 9. The drainage tube leading from the wound passes through the opening 6 in the apron and the end passes into the bottle 10. From the above it will be seen that I have provided means whereby the device may be 85 quickly and easily attached or detached for cleaning purposes and will be comfortable to the wearer. The bottle being attached to the apron will allow new bottles to be substituted without removing the apron. By 90 providing such a bottle and apron, I do away with all obnoxious odors resulting from the discharge from the wound.

Having fully described my invention what I claim as new and desire to secure Letters 95 Patent is:

A drainage bottle including an apron provided with an opening therein, said apron

having its lateral margins adjacent its upper end, extended to form laterally projecting ears, a vertically extending ear formed on the upper end of said apron, a bottle secured to said apron and positioned below said opening, buckles secured to said ears, a waist strap having its opposite ends buckled to said lateral ears, and a shoulder strap hav-

ing one end secured to said waist strap and the opposite end buckled to said vertical ear. In testimony whereof I affix my signature in presence of two witnesses.

WILLIAM FILLMORE WOFFORD.
